UNITED STATES PATENT OFFICE

OTTO J. GROEHN, OF GROSSE POINTE PARK, AND LAWRENCE S. LAMB, OF GROSSE POINTE, MICHIGAN, ASSIGNEES TO HUDSON MOTOR CAR COMPANY, OF DETROIT, MICHIGAN, A CORPORATION OF MICHIGAN

APPARATUS FOR SHAPING SHEET METAL

Original application filed December 28, 1927, Serial No. 243,030. Patent No. 1,708,615, dated April 9, 1929.
Divided and this application filed February 8, 1929. Serial No. 338,467.

This invention relates to apparatus for shaping sheet metal and more particularly to apparatus for turning inward the body of a sheet metal strip having a flange offset by folding a portion of the flange over the body.

The application is a division of our co-pending application Serial No. 243,030 filed December 28, 1927, Patent No. 1,708,615, dated April 9, 1929, which discloses a method 10 of shaping sheet metal to produce a quarter window finish molding for an automobile body.

It is the object of the present invention to provide an apparatus which is particularly 15 suitable for turning inward a portion of the body over which the flange is folded in the practice of the method described in our above mentioned co-pending application.

The invention will be more clearly understood from the following description in conjunction with the accompanying drawings, in which:

Fig. 1 is a plan view of the lower half of an apparatus embodying the invention;

Fig. 2 is a side elevational view of the same; and

Figs. 3, 4, 5 and 6 are sectional views taken upon line 3—3, Fig. 2.

Before explaining in detail the present invention, it is to be understood that the invention is not limited in its application to the details of construction and arrangement of parts illustrated in the accompanying drawings, since the invention is capable of 30 other embodiments and of being practiced or carried out in various ways. Also it is to be understood that the phraseology or terminology employed herein is for the purpose 35 of description and not of limitation, and it is not intended to limit the invention beyond the terms of the several claims hereto appended as considered in view of the prior art and the requirements thereof.

The apparatus of the invention is adapted 45 particularly for shaping a sheet metal blank previously formed with offset flanges 7a and 7b and having a projecting body portion 7c. One embodiment of the invention is illustrated by the apparatus shown in the drawings which comprises a base 15 having a

block 16 secured in any suitable manner, as by screws 17, to the top surface of the base near one side thereof for supporting the body of the blank with a flange overhanging and engaging the side of the block. A plurality of projections 18 extend upwardly at one side of the base and have wearing blocks 19 secured to their inner upper edges in any suitable manner, as by bolts 20. A lower die member 22 is mounted for movement along the top surface of the base between the projections 18 and the block 16. A hardened die block 23 having a cam surface 27 is secured upon the inner upper edge of the die 22, as by screws 24, and a hardened wearing block 25 is secured to the upper outer edge of the die, as by screws 26.

The die 22 normally is held away from the block 16 in any suitable manner. As illustrated, a bracket 28 is secured to the base, as by bolts 29, and is provided near its upper end with an opening 30 adapted to permit the free passage of a bolt 31 secured to the die 22. A spring 33 surrounds the bolt 31 and extends between the outer surface of the bracket 28 and a washer 34 positioned and held near the outer end of the bolt, as by nuts 35.

A ram 36 is adapted for movement towards and from the base and for this purpose is provided with openings 37 for collars 38 adapted to receive for sliding engagement therewith suitable guides 39 fixed in the base. A hardened upper die block 40 is secured to the lower surface of the ram 36, as by screws 41, and is positioned to engage and shape a portion of the body of the blank around the lower die block 23.

A recess 44 is provided in the lower surface of the ram to receive for movement therein a work gripping member 45 which is secured to the ram by bolts 46 secured to the member 45 and passing through openings 47 in the ram provided with shoulders 48 adapted to engage the head of the bolt and serve as a stop. The member 45 normally is held in extended position by springs 50 positioned in recesses 51 in the ram and engaging the top surface of the member 45. A cam 55 is secured near one edge of the ram

36 as by bolts 56 and depends therefrom so as to enter the space between the blocks 19 and 25 upon the projections 18 and lower die 22 respectively.

5 To turn the projecting portion 7e of the body of the blank inward the blank is supported in inverted position upon the block 16 with the flanges 7b overhanging and engaging the side of the block. The ram 36 is then 10 lowered to bring the work gripping member 45 into engagement with the body of the blank and hold the same yieldingly against the member 16. At the same time the cam 55 engages the cam surface 27 upon the lower die and moves the latter into engagement with the flanges 7b of the blank and holds the same against the side of the block 16 thereby positioning the lower die block 23 beneath the portion 7e of the body of the 20 blank. Upon further downward movement of the ram, the upper die block 40 is brought into engagement with the portion 7e of the body of the blank and shapes the same against the lower die block 23 to turn the portion 7k 25 inwardly.

What we claim is:

1. In an apparatus for shaping sheet metal previously folded with an offset flange, the combination of a member for supporting the 30 body of the metal sheet with the flange overhanging and normally resting thereagainst, a lower die movable under a portion of the body of the metal sheet to bring one side thereof against said flange and hold it against said member, and an upper die movable to shape said portion over said lower die and against another side thereof.
2. In an apparatus for shaping sheet metal previously folded with an offset flange, the 40 combination of a member for supporting the body of the metal with the flange overhanging and normally resting thereagainst, a lower die movable under a portion of the body of the metal to hold said flange against said member, an upper die movable to shape said portion against said lower die, and means for holding the main portion of the body against said member.
3. In an apparatus for shaping sheet metal 50 previously folded with an offset flange, the combination of a member for supporting the body of the metal with the flange overhanging and normally resting thereagainst, a lower die movable under a portion of the body of the metal to hold said flange against said member, an upper die movable to shape said portion against said lower die, means for holding the main portion of the body against said member, and means normally holding the lower die away from said member.
4. In an apparatus for shaping sheet metal 60 previously folded with an offset flange, the combination of a member for supporting the body of the metal with the flange overhanging and resting thereagainst, a lower die

movable under a portion of the body of the metal to hold said flange against said member, means normally holding the lower die away from said member, a ram movable toward and from the lower die, a cam on said ram for moving the lower die to hold the flange against said member, an upper die mounted on said ram to engage and shape said portion of the body to the metal against the lower die, and a gripping member yieldingly mounted in said ram and adapted to hold the main portion of the body against said supporting member.

In testimony whereof we affix our signatures.

OTTO J. GROEHN.
LAWRENCE S. LAMB.
